UNITED STATES PATENT OFFICE.

HUGO BORCHARDT, OF CHARLOTTENBURG, GERMANY.

DEVICE FOR RETAINING THE BREECH-BLOCK OF AUTOMATIC FIREARMS IN THE REARWARD POSITION WHEN THE MAGAZINE IS EMPTY.

1,196,759.

Specification of Letters Patent. Patented Sept. 5, 1916.

Application filed October 2, 1912. Serial No. 723,582.

To all whom it may concern:

Be it known that I, HUGO BORCHARDT, a citizen of the United States of America, residing at 31 Kantstrasse, Charlottenburg, 5 near Berlin, in the German Empire, have invented a certain new and useful Improvement in Devices for Retaining the Breech-Blocks of Automatic Firearms in the Rearward Position When the Magazine is 10 Empty, of which the following is a specification.

The invention relates to a device for firearms for locking the breech block in the rearward position when the magazine is 15 empty. In the known devices of this kind the breech block is held in the open position by locking members which form a bearing, which are rigid in themselves and which therefore suffer considerably from the 20 shocks particularly in the case of self loaders in which the closing springs are relatively strong.

The present invention has for its object a device in which, contrary to what is the 25 case in these known devices with rigid bearing, the breech closure is held by a spring engaging device and is therefore resiliently supported so that the interengaging faces of the locking member and of the breech block 30 are secured from injury due to shock and the like even with the strongest closing springs.

An embodiment of the invention is illustrated in the accompanying drawing, in 35 which—

Figures 1, 2 and 3 illustrate the device in longitudinal section in three different positions.

The locking lever *a* is formed as a rod 40 which is mounted in such a manner as to be displaceable longitudinally beneath the path of the breech block in the grip *g*. When the magazine is empty the rear nose *p'* of the cartridge feed device *p* engages 45 beneath its front nose *a'* and presses it upward so that this nose *a'* engages in a recess *k'* of the breech closure which again moves forward after the recoil. On the rear end of the locking lever on its lower face a stirrup- 50 shaped projection *a''* is provided and engages a stud *g'* on the grip so that the locking lever is rotatable about this stud and displaceable in the forward direction. The front face of this stirrup *a''* is provided with 55 a nose *a'''* which engages in a recess in the

head *b'* of a bolt *b* which is arranged beneath the locking lever *a* in a recess in the breech block, its head being constantly pressed by a spring *f'* rearward against the stirrup *a''*. The rear chamfered end of the 60 bolt is guided in a hemispherical insertion *b''* and the recess in the breech closure which is circular in front merges into an oval at the rear so that the bolt is able to rotate in a vertical plane about its horizontal axis with 65 the insertion. The nose *a'''* of the locking lever is located beneath the plane passing through the axis of rotation of the locking lever and of the bolt *b* so that the bolt always tends to depress the nose *a'* of the 70 locking lever.

So long as the cartridge feed device *p* is not acting on the locking lever this lever is held in the releasing position (Fig. 1). If, however, when the magazine is empty 75 the nose *p'* of the feed device presses upon the nose *a'* of the locking lever the latter is rotated in opposition to the action of the spring *f'* in such a manner that its nose enters the path of the breech block and retains it when it moves forward after firing (Fig. 2). The head of the bolt *b* is also 80 pressed upward while the nose *a'''* of the locking lever remains below the plane passing through the axis of rotation of the locking lever and of the bolt. The breech block *k* which moves forward after the recoil, its recess *k'* coming into engagement with the locking nose *a'* presses the locking lever *a* forward in compressing the spring *f* (Fig. 85 3) and is then pressed back into the initial engaging position (Fig. 2) by the spring *f'* which is stronger than the closing spring *f*. When after the insertion of a new full 90 magazine by drawing back the breech closure the locking nose *a'* is released therefrom the locking lever *a* is rotated back into its initial position (Fig. 1) by the spring bolt *b*.

What I claim and desire to secure by 100 Letters Patent of the United States is:—

1. In a firearm, the combination of a breech block, a breech closing spring, a member locking said breech block in its rearward position when the magazine is empty and capable of longitudinal movement, a spring 105 acting on said locking member to retain same in its inoperative position, and a magazine follower engaging said locking member and bringing same into engagement with 110

said breech block against the action of said spring when the magazine is empty.

2. In a firearm the combination of a breech block, a breech closing spring, a lever locking said breech block in its rearward position when the magazine is empty and capable of longitudinal and rotary movement, a spring pressed bolt bearing against an extension of said locking lever in such a manner as to tend to retain said lever in its inoperative position, and a magazine follower engaging said locking lever and bringing a tooth on said lever into engagement with a recess in said breech block against the action of said bolt spring when the magazine is empty.

3. In a firearm the combination of a breech block, a breech closing spring, a le-

ver locking said breech block in its rearward position when the magazine is empty and 20 capable of longitudinal and rotary movement, a spring pressed bolt guided in a rotatably mounted member and bearing against a downwardly extending portion of said locking lever and a magazine follower 25 engaging said locking lever and bringing a tooth on said lever into engagement with a recess in said breech block against the action of said bolt spring when the magazine is empty.

In testimony whereof I affix my signature in presence of two witnesses.

HUGO BORCHARDT.
